UNITED STATES PATENT OFFICE

2,541,212

FRICITION SHOCK ABSORBER FOR
RAILWAY CAR TRUCKSGeorge E. Dath, Mckena, Ill., assignor to W. H.
Miner, Inc., Chicago, Ill., a corporation of Dela-
ware

Application April 14, 1949, Serial No. 87,383

3 Claims. (Cl. 267—9)

1

This invention relates to improvements in friction shock absorbers especially adapted for use as snubbing means for railway car truck springs.

One object of the invention is to provide a shock absorber adapted to be substituted for one of the spring units of a cluster of truck springs of a railway car, comprising a pair of relatively slidable friction elements having their movement toward each other opposed by spring means, wherein one of the friction elements is provided with opposed friction surfaces and the other element is in the form of a plate engaged between said friction surfaces, and wherein said elements are forcibly tilted to frictionally engage the same with each other.

A more specific object of the invention is to provide a mechanism as set forth in the preceding paragraph wherein the relatively slidable friction elements, which are forcibly tilted to bring the same into frictional engagement with each other, have their movement toward each other opposed by spring means which also acts to effect the relative tilting of said elements.

Other objects of the invention will more clearly appear from the description and claims hereinafter following.

In the accompanying drawing forming a part of this specification, Figure 1 is a transverse, vertical sectional view of my improved shock absorber. Figure 2 is a horizontal sectional view, corresponding substantially to the line 2—2 of Figure 1 with the spring omitted. Figure 3 is a bottom plan view of the top friction member illustrated in Figure 1. Figure 4 is a side elevational view, looking from right to left in Figure 3.

My improved shock absorber, as illustrated in the drawing, comprises broadly a top friction member A, a bottom friction member B, and a spring resistance C.

The top friction member A is formed integral with a disc-like follower 10 from which this friction member depends. The friction member A comprises laterally spaced side walls 11—11 connected by relatively heavy, transverse, spaced webs 12 and 13, located at opposite sides of the central vertical axis of the mechanism. The walls 11—11 and the web 12 are formed integral with the follower disc 10. The web 13 is spaced an appreciable distance from the follower 10, being located at the lower ends of the side walls 11—11 and the web 12 extends downwardly from the follower 10, having its lower end terminating above the upper end of the web 13. Each web

2

12 and 13 presents a vertically extending, flat friction surface on its inner side, the friction surface of the web 12 being indicated by 14 and that of the web 13 being indicated by 15.

5 The follower 10 has its top side rounded off to provide a substantially convex bearing surface 16 to facilitate rocking of the follower 10 on the top spring plate of the usual cluster of truck springs. The follower 10 presents a peripheral flange 17, which is downwardly thickened, or crowned, at the left hand side, as seen in Figure 1, said crowned portion being indicated by 18.

15 The bottom friction member B carries a disc-like follower plate 19 at its base, which plate is formed integral therewith. The follower plate 19 of the friction member B is opposed to the follower plate 10 and corresponds to the latter in size.

20 The friction member B is in the form of an upstanding, relatively thick plate engaged between the webs 12 and 13 of the friction member A and having lengthwise extending, flat friction surfaces 20—20 on opposite sides thereof engaged respectively with the friction surfaces 25 14 and 15 of the webs 12 and 13.

25 The follower plate 19 presents a peripheral flange 21, which is upwardly thickened, or crowned, at the left hand side of the mechanism, as seen in Figure 1, said crowned portion being indicated by 22. The bottom side of the follower plate 19 is rounded off to provide a substantially convex bearing surface 23 to facilitate rocking of the follower on the bottom spring follower plate of the usual cluster of truck springs. Both follower plates 10 and 19 are provided with outwardly opening central seats 24—24 adapted to accommodate the spring centering projections of the usual top and bottom spring plates of a cluster of truck springs.

40 The spring C is in the form of a helical coil surrounding the friction members A and B and bearing at its top and bottom ends, respectively, on the followers 10 and 19. As will be evident, due to the followers 10 and 19 being crowned at the left hand side of the mechanism, as seen in Figure 1, the left hand side portion of the spring C is under greater compression than the right hand side portion, thus urging the friction members A and B to tilt with respect to each other, thereby effecting binding action between the same to bring the friction surfaces thereof into tight engagement.

45 My improved shock absorber replaces one or more of the spring units of a truck spring cluster of a railway car, being interposed between the

usual top and bottom spring plates, which cooperate with the cluster.

The operation of my improved shock absorber is as follows: Upon the spring cluster of the truck of a railway car being compressed between the follower plates of said cluster, the shock absorber, which is disposed between said follower plates, is compressed therewith, thereby forcing the friction member A downwardly against the resistance of the spring C, sliding the friction surfaces 14 and 15 of the member A on the platelike friction member B, the friction surfaces being held in intimate contact due to action of the spring C, which tends to tilt the members A and B with respect to each other.

During this lengthwise sliding movement of the friction members A and B on the engaging friction surfaces, the required frictional resistance is developed to effectively snub the action of the truck springs.

I claim:

1. In a friction shock absorber, the combination with a friction plate having lengthwise extending friction surfaces on opposite sides thereof; of a friction unit having a pair of lengthwise extending, opposed, interior friction surfaces, one of said surfaces being staggered with respect to the other lengthwise of the unit; said opposed, interior friction surfaces engaging the plate at opposite sides and having sliding contact with the friction surfaces of the latter; said plate and unit being supported for relative tilting movement, said plate and unit having spring abutments thereon; and spring means interposed between said abutments to yieldingly oppose movement of said plate and unit toward each other; said spring means being under greater compression at one side of the mechanism than at the other, between said abutments, for urging the same to tilt with respect to each other.

2. In a friction shock absorber, the combination with an end follower having a crown on the inner side thereof at one side of the mechanism; of a second end follower having a crown on the inner side thereof located at the same side of the mechanism as the crown of said first named follower, each of said followers having a convex outer sur-

face on which it is supported for tilting movement, said followers being relatively movable toward and away from each other lengthwise of the mechanism; a friction plate on said first named follower extending toward the second named follower, said plate having friction surfaces on opposite sides thereof; a friction unit on said second named follower, projecting toward said first named follower, said unit having a pair of laterally spaced, interior, lengthwise extending friction surfaces embracing said plate and engaging the friction surfaces of the same; and a spring surrounding said plate and friction unit and bearing at opposite ends on said followers and the crowns thereof.

3. In a friction shock absorber, the combination with a top follower having a rounded top surface, said follower having a depending crown on the lower side thereof at one side of the mechanism; of a friction unit depending from said follower, said unit having a pair of laterally spaced, opposed, interior, lengthwise extending friction surfaces thereon; a bottom follower having a rounded bottom surface, said bottom follower having a raised crown on the upper side thereof located at the same side of the mechanism as the crown of said top follower; a friction plate upstanding from said bottom follower and engaged between the friction surfaces of said friction unit in sliding frictional engagement with said surfaces; and a coil spring surrounding said unit and plate and bearing at its top and bottom ends on said top and bottom followers and the crowns thereof.

GEORGE E. DATH.
